(57) **CLAIM**

The ornamental design for a connector with illumination region, as shown and described.

DESCRIPTION

FIG. 1 is a top front isometric view of a connector with illumination region in a non-illuminated state showing our new design;

FIG. 2 is a right side view thereof;

FIG. 3 is a left side view thereof;

FIG. 4 is a top view thereof;

FIG. 5 is a bottom view thereof;

FIG. 6 is a front view thereof;

FIG. 7 is rear view thereof;

FIG. 8 is a top front isometric view of the connector of FIGS. 1-7 showing the illumination region in an illuminated state;

FIG. 9 is a right side view thereof;

FIG. 10 is a left side view thereof;

FIG. 11 is a top view thereof;

FIG. 12 is a bottom view thereof;

FIG. 13 is a front view thereof;

FIG. 14 is rear view thereof;

FIG. 15 is a top front isometric view of the connector of FIGS. 8-14 showing the illumination region in an illuminated state in grayscale;

FIG. 16 is a right side view thereof;

FIG. 17 is a left side view thereof;

FIG. 18 is a top view thereof;

FIG. 19 is a bottom view thereof;

FIG. 20 is a front view thereof; and,

FIG. 21 is rear view thereof.

The broken line showing of various features of the connector are for environmental purposes only and form no part of the claimed design. The radiating lines emanating from the circle in FIGS. 8-14, and the oval shown in grayscale in FIGS. 15-21 represent illumination.
